Primary Examiner — R. Johnson(74) *Attorney, Agent, or Firm* — George D. Morgan(57) **CLAIM**

The ornamental design for an electronic piano, as shown and described.

DESCRIPTION

FIG. 1 is a front perspective view of an electronic piano, showing my new design; the electronic piano shown in an opened condition;

FIG. 2 is a rear perspective view thereof;

FIG. 3 is a front perspective view thereof; the electronic piano shown in a closed condition;

FIG. 4 is a front view of FIG. 1;

FIG. 5 is a rear view thereof;

FIG. 6 is a left side view thereof;

FIG. 7 is a right side view thereof;

FIG. 8 is a top view thereof;

FIG. 9 is a bottom view thereof; and,

FIG. 10 is an enlarged, partial view of the portion taken at line-10 in FIG. 1.

The broken lines in the drawings illustrate the portions of the electronic piano, which form no part of the claimed design. The dash-dot-dash broken lines encircling the enlarged views are for annotative purposes only and form no part of the claim thereof.
